CLAIM

An ornamental design for a ratchet wrench or similar article, substantially as shown in FIGS. 1-14 and as herein described.

DESCRIPTION

FIG. 1 is a pictorial view of a ratchet wrench in accordance with the present invention.

FIG. 2 is a top plan view thereof.

FIG. 3 is a bottom plan view thereof.

FIG. 4 is a right side elevation thereof.

FIG. 5 is a left side elevation thereof.

FIG. 6 is a front elevation thereof.

FIG. 7 is a rear elevation thereof.
